UNITED STATES PATENT OFFICE.

NORMAN B. HUFFMAN, OF GRANT, INDIANA.

GATE.

SPECIFICATION forming part of Letters Patent No. 295,641, dated March 25, 1884.

Application filed September 13, 1883. (No model.)

To all whom it may concern:

Be it known that I, NORMAN B. HUFFMAN, a citizen of the United States, residing at Grant, in the county of Fulton and State of Indiana, have invented certain new and useful Improvements in Gates, of which the following is a specification, reference being had therein to the accompanying drawings.

This invention relates to improvements in gates, and has for its object to enable the gate to be raised and lowered to prevent the clogging up of snow, or to let sheep or hogs pass through where other stock is not wanted. These objects are attained by the mechanism illustrated in the accompanying drawings, forming a part of this specification, in which—

Figure 1 is a side elevation. Fig. 2 is a detail view of the brace F.

The letters A A' indicate the gate-posts; B, the gate.

D is the connecting-rod, which is secured to the gate-post A by the eyebolts E.

F is a brace secured to the connecting-rod D in such manner that it turns freely thereon. The lower end of the rod or brace F is formed into a hook, which enters the holes G G' G" in the vertical piece H, and is intended to hold the gate when elevated, and also acts as a

brace to the gate itself. The end of the hook F' is provided with a hole to insert a key, to hold the brace F when inserted in either of the holes G G' G" and prevent its slipping out.

J is a hook or latch which engages with staples or catches J' on post A'. The staples or catches J' are placed at proper distances apart to enable the gate to be fastened when shut, according to the height to which it may have been set.

Having described my invention, what I desire to secure by Letters Patent and to claim is—

The gate-frame having central vertical piece, H, provided with a series of perforations, G G' G", in combination with vertical rod D, secured to the gate-post A, and provided with swinging angled piece F, having flange F', for engaging with the perforations G G' G" in the piece H, and thereby securing the vertical adjustment of the gate, substantially as specified.

In testimony whereof I affix my signature in presence of two witnesses.

NORMAN B. HUFFMAN.
